UNITED STATES PATENT OFFICE.

EDWARD T. HURLEY, OF CINCINNATI, OHIO.

DESIGN FOR A PLAQUE OR SIMILAR ARTICLE.

Application filed March 12, 1928. Serial No. 25,798. Term of patent 7 years.

To all whom it may concern:

Be it known that I, EDWARD T. HURLEY, a citizen of the United States of America, and a resident of Cincinnati, in the county of Hamilton and State of Ohio, have invented a new, original, and ornamental Design for a Plaque or Similar Article, of which the following is a specification, reference being made to the accompanying drawing, forming a part thereof.

Figure 1 is a top plan view of a plaque or similar article showing the design.

Figure 2 is a side elevation of the plaque shown in Fig. 1.

Fig. 3 is a vertical cross-section on the line 3—3 of Fig. 1.

I claim:

The ornamental design for a plaque or similar article as shown.

EDWARD T. HURLEY.
